[57] CLAIM

The ornamental design for a pump cassette for an IV pump apparatus, substantially as shown and described.

DESCRIPTION

FIG. 1 is a top plan view of a pump cassette for an IV pump apparatus;

FIG. 2 is a side elevational view;

FIG. 3 is a front elevational view;

FIG. 4 is a side elevational view opposite FIG. 2;

FIG. 5 is a rear elevation view; and

FIG. 6 is a bottom plan view.

The broken line showing of IV tubing in FIGS. 2, 3 and 4 is for illustrative purposes only.
